UNITED STATES PATENT OFFICE.

WAYNE RAWLEY, OF PITTSBURGH, PENNSYLVANIA, ASSIGNOR TO BLAW STEEL CONSTRUCTION COMPANY, OF HOBOKEN, PENNSYLVANIA, A CORPORATION OF NEW JERSEY.

COLLAPSIBLE BOX.

1,186,497.

Specification of Letters Patent.

Patented June 6, 1916.

Application filed March 23, 1914. Serial No. 826,493.

To all whom it may concern:

Be it known that I, WAYNE RAWLEY, a citizen of the United States, and residing in the city of Pittsburgh, in the county of Allegheny and State of Pennsylvania, have invented or discovered new and useful Improvements in Collapsible Boxes, of which the following is a specification.

My invention consists of a new and improved collapsible shipping box or container.

Although particularly intended for a piano box, the principles of my invention may be applied to a collapsible container used for any purpose.

The object in view is the provision of an inexpensive, light-weight box, which when set up or extended will properly protect its contents both from damage from rough usage and from the weather and which may be knocked down or collapsed for return shipment or storage into small compass. The wooden boxes now in general use for shipping pianos after one use are thrown aside while a suitable collapsible box may be used over and over again. For the accomplishment of these purposes in view, I provide a box comprising hinged together elements or portions, each portion being composed of a strong and rigid, yet light frame of angled or flanged metal bars with a filling of stout sheet material, such as fiber-board, to protect the piano from rough usage and the weather. The filling of the bottom element is preferably composed of sheet or plate metal for the sake of strength.

The methods of folding the elements together into compact form and of hinging the same together are novel, as are also the means for supporting and securing said members in position when the box is set up. Novel means are also provided for supporting the piano within the box and in securing the same in place.

Many other novel features of construction and arrangement of parts will appear from the following description.

In the accompanying drawings, Figure 1 is a perspective of the box set up and closed, supposedly containing a piano ready for shipment; Fig. 2 is a similar view showing the empty box with the lower lid raised to show construction; Fig. 3 is a perspective showing the box collapsed with the exception of one of the sides, the means for locking the box in its knocked down state being

omitted to prevent confusion; Fig. 4 is a rear elevation of the box; Fig. 5 is an enlarged detail showing the method of hinging together the lid and front and of securing the same to the sides when the box is set up. Fig. 6 is a section taken along the line VI—VI in Fig. 5; Fig. 7 is a vertical cross-section of the box set up taken along the line VII—VII in Fig. 4, the transverse bracing angle-irons of the lid and front being omitted to avoid confusion; Fig. 8 is an enlarged detail, partially in section, showing one of the hook bolts by means of which the lid and front are secured to the sides when the box is set up; Fig. 9 is a similar view showing one of the hook bolts by means of which the top is secured to the sides when the box is set up; Fig. 10 is an enlarged detail of the structure shown in Fig. 2 showing the method of securing the front to the bottom when the box is set up and also the means of supporting the front ends of the rails from the bottom; Fig. 11 is an enlarged broken plan showing the method of locking the two sides together and down upon the remaining elements when the box is knocked down; Fig. 12 is an enlarged detail of the sliding shutter attached to the inner face of the back to seal unused lag screw holes; Fig. 13 is an enlarged detail in perspective showing the method of hinging the sides to the back, the side being shown folded or collapsed, while Fig. 14 is a similar view showing the side set up; Fig. 15 is a vertical section along the line XV—XV in Fig. 16 showing the method of hinging the bottom to the back; Fig. 16 is a view of the same taken along the line XVI—XVI in Fig. 15; Fig. 17 is a broken side elevation showing the mounting of the rear ends of the rails upon the bottom, and Fig. 18 is a broken plan view showing the mounting of the front end of the rails upon the bottom.

The following is a detailed description of the drawings.

A is the back of the box which forms the base or foundation of the structure; B and B' are the sides which are hinged to the back; C is the bottom hinged to the back; D is the top hinged to the back; E is the lid hinged to the top and F is the front hinged to the lid. The back A is composed of edge angle-irons 1^a and vertical and transverse angle-iron braces 2^a.

3^a are the corner plates connecting adja-

cent ends of angle-irons. Secured to the inner faces of said angle-irons is a filling of fiber board 4^a.

It will be observed that while the free flanges of the angle-irons 2^a and of the horizontal top angle-iron 1^a extend rearwardly or outwardly from the interior of the box, the angle-irons 1^a at the vertical side edges and the horizontal bottom edge of the back 10 extend forwardly to engage the bottom and sides of the box when the latter is set up. The sides B and B' are similarly composed of edge angle-irons 1^b and transverse and horizontal cross bracing angle-irons 2^b.

15 3^b are the corner plates and 4^b the fiber filling. The free flanges of the angle-irons of said sides, except those of the top and bottom angle-irons 1^b are turned outwardly, that is away from the interior of the box.

20 5 are brackets secured to the corners of the back A and provided with slideways 6 which have at their outer ends headed pins 7 which engage the slotted plates 8 secured to the rear of the top and bottom of the sides B and B'. By this means said sides are pivotally connected to the back in such a manner that before being folded down upon the other elements when the box is collapsed, they may first be drawn away from the back 25 and then folded down parallel with the latter so that a space is left between the said sides and back to contain the top and lid and front.

30 The bottom C is composed of edge angle-irons 1^c and transverse and intermediate angle-irons 2^c. The free flanges of said angle-irons are upturned and to the outer or lower face of the same is secured the sheet or plate metal bottom 4^c. When the box is 35 set up, the bottom C occupies the position shown in Fig. 2, its rear and side edge angle-irons 1^c nesting in the bottom angle-irons of the back and sides, thus supporting the bottom and its burden by the back and sides.

40 45 9 represents a pair of elevated rails supported by and running transversely of the bottom C to support the base of the piano with its casters out of contact with the bottom proper and the rails. Said rails are 50 preferably of substantially inverted U-shape in cross-section and are supported as follows: The front end of a rail is attached thus. 10 is a vertical plate riveted to the free flange of the front angle-iron 1^c and to such plate 10 is riveted a three-sided bracket 11 extending horizontally and embracing the forward end of the rail 9 and riveted thereto. The rear end of the rail is 55 embraced by and riveted to a three-sided bracket 12 which in turn is riveted to the free flange of the rear edge angle-iron 1^c of the bottom. Vertical slots 13 are provided in the bracket 12 and the rail 9, as shown in Fig. 17. 14 is a similar bracket riveted 60 to one of the vertical angle-irons 2^a of the

back A and extending inwardly through an aperture in the filling 4^a to embrace the upper portion of the bracket 12 and the end of the rail 9. A pin 15 extends through registering holes in the bracket 14 and the slots 13, thus by means of the two rails pivoting the bottom C to the back A. By means of slots 13, the weight of the bottom and its burden, when the box is set up does not rest on the hinges but upon the flanges 75 along the bottom edges of the back and sides as before stated.

80 The top D is formed of edge angle-irons 1^d and such transverse braces which may be considered necessary. As the construction and arrangement of the latter is sufficiently illustrated in the showing of the other elements, the same are omitted in the case of the top for the sake of clearness. The free flanges of the angle-irons 1^d are inturned or 85 downturned, as shown in Fig. 7 and 4^d is the filling of fiber board secured to said angle-irons.

90 When the box is set up, the top edge angle-iron 1^a of the back A nests in the rear edge angle-iron 1^d of the top, while the side edge angle-irons 1^d of the top nest in the top angle irons 1^b of the sides B and B'. The top edges of the sides are given a forward slope so as to incline the top of the box to 95 shed water.

100 16 represents hinges having their plates inserted between the flanges of the angle-irons 1^a and 1^d, as shown in Fig. 7 and riveted thereto respectively, said flanges being bent apart slightly to admit of the hinge. Thus the top when raised, and the box set up, rests upon the top edge of the back, while in knocking down the box, said lid may be dropped down flat against the 105 inside face of the said back.

110 17 are hook bolts provided with wing nuts 18 and extending through the top angle-iron 1^b of the sides and slots 19 in the top and adapted to engage the depending flanges 110 of the side angle-irons 1^d. By turning the bolts 90 degrees and tightening the nuts, the bolts may be locked tightly in place as shown in Figs. 7 and 9.

115 The front of the box is provided with a closure by means of which the box is enclosed when in use. Said closure is in two parts hinged together and comprising the lid E hinged to the top D and the front F hinged to the lid E.

120 The lid E is hinged at its top edge to the front edge of top D and is composed of a fiber-board filling 4^e framed by edge angle-irons 1^e and transverse angle-irons 2^e and corner plates 3^e, the free flanges of the angle-irons being out turned.

125 20 are the hinges whose plates are inwardly inserted between the top angle-iron of the lid E and the front angle-iron of the top D and riveted as shown in Fig. 7. The 130

flanges of the sides of lid E are provided with hook bolts 21 having wing nuts 22, which hook bolts when the lid is closed in place engage with and are tightened up 5 against the side edge flanges of the sides B and B'.

The front F is of similar construction, being composed of edge angle-iron 1^t, transverse angle-irons 2^t and corner plates 3^t, 4^t 10 representing the fiber-board filling. Said front F is hinged to the bottom edge of lid E by means of hinges 23 as shown in Fig. 7, and the lower edge of the front F is provided with locking bolts 24 which when said 15 lid is closed engage the slotted brackets 25 on the front edge of the bottom C. The front F is also similarly securable to the sides B and B', as is the case with lid E, hook bolts 21 and wing nuts 22 being provided for that purpose.

To hold the piano rigidly in place in the box during shipment and handling, lag screws extending through the back of the box and engaging the back of the piano, 25 similar to those used in the case of the ordinary wooden box, are provided. As the height of various makes and sizes of pianos vary, I provide for the accommodation of the upper or top lag screws a plurality of 30 holes 26 arranged in vertical rows through the vertical angle-irons 2^t of the back at either side and through the fiber 4^a. Thus the lag screws may be inserted at the proper height to properly engage the piano. To 35 close the holes 26 which may not be engaged by lag screws I secure a sliding channel plate 27 attached to the inner face of the fiber 4^a in alignment with each vertical row of holes 26. Said plate is slidingly held in 40 place by means of bolts 28 extending through the back A which by tightening hold the channel plate in place to seal the unused holes 26. The plate is provided with holes 29 so spaced that when one of the 45 holes 29 registers with one of the holes 26 to admit the entrance of a lag screw, the remaining holes 26 of the row are sealed against the entrance of dirt or moisture. Holes 26^a are also provided through the 50 angle-irons 2^a for the lower lag screws. The horizontal cross-braces 2^b of the sides B and B' are provided with holes 30 so that workmen may use the usual hooks in lifting and moving the box and its contents.

55 To hold the collapsed box together for shipment, I may use any convenient means. I have indicated in Fig. 11 a strap 31 secured to the outer face of the side B by means of headed pin 32 which engages a slot 33 in said strap. The other end of the strap is provided with a bayonet slot 34 which may engage a headed pin 35 on the outer face of the other side B'. The sides may thus be locked down upon the rest of the elements. 60 65 I have shown as a convenient structure the

frame work of the elements composed of angle-iron but it will be understood that said term as used includes also channels, bent or pressed plates or other shapes.

The use of my box is as follows: Assuming the box to contain a piano to be closed as in Fig. 1, the bolts 24 and 21 are loosened and disengaged from the brackets 25 and flanges 1^b, respectively and the front folded up against the lid, as shown in Fig. 2. Both front and lid are then raised and laid back on the top. The lag screws are then loosened and the piano pulled forwardly out of the box. To collapse the box, it is laid on its back and the bottom C folded down on the latter. The bolts 17 are then loosened and turned to disengage them from the flanges 1^d and to permit their passage through the slots 19 in the top, and the top is then folded down on the back A and the 85 folded together lid and front laid on the bottom C. The sides B and B' are next folded down upon the top and front. To set up the box, the two sides are first unfolded and run back into place. The front 90 and lid are then lifted from the bottom and the latter turned down into engagement with the bottom flanges of the back and sides. The front and lid are then unfolded from the top, and the latter raised and secured to 95 the sides and the front and lid may then be unfolded and secured in place by means of the bolts 21 and 24. The bolts 17 are used to hold the top up against the top flanges of the sides.

100 It is evident from the foregoing that my improved collapsible box is of very light and inexpensive construction but still possesses ample strength and rigidity for the purposes required; that the same may be readily knocked down or set up, and that the same may be packed into a small compass for return shipment.

105 Although for the sake of clearness I have minutely described the embodiment of my invention shown in the drawings, I do not wish to limit myself thereby but

I claim broadly—

110 1. A collapsible box consisting of a back; sides hinged to said back; a bottom hinged to said back and adapted to fold up against the same but when extended being supported by the bottom edges of said back and sides; a top hinged to said back and adapted to fold down against the same but when extended being supported by said sides, and a closure hinged to said top and adapted to fold down upon said bottom but when extended being secured to said sides, and said sides when collapsed folding down upon 115 said bottom, top and closure.

120 2. A collapsible box consisting of a back; sides hinged to said back; a bottom hinged to said back and adapted to fold up against the same but when extended being supported by 125 said sides, and a closure hinged to said top and adapted to fold down upon said bottom but when extended being secured to said sides, and said sides when collapsed folding down upon 130 said bottom, top and closure.

ed by the bottom edges of said sides and back; a top hinged to said back and adapted to be folded down against the same but when extended being supported from above 5 by said sides; a lid hinged to said top and adapted to be folded down upon said bottom, and a front hinged to said lid and adapted to be folded up against the same, said sides when collapsed folding down upon said bottom, top, lid and front.

3. A collapsible box consisting of elements associated together in hinged relationship, said elements comprising a back; a bottom hinged to said back and adapted to be folded 15 up against the same; a top hinged to said back and adapted to be folded down against the same; a closure hinged to the front edge of said top and adapted to be folded down upon said bottom, sides, and sliding hinged 20 connection between said sides and said back permitting said sides to be drawn away from said back before folding whereby said sides may be folded flat upon said bottom, top and closure.

25 4. A collapsible box consisting of elements associated together in hinged relationship, said elements comprising a back; a bottom hinged to said back and adapted to be folded up against the same; a top hinged to said 30 back and adapted to be folded down against the same; a lid hinged to said top and adapted to be folded down on said bottom; a front hinged to said lid and adapted to be folded back on said lid, sides, and sliding hinged 35 connection between said sides and said back permitting said sides to be drawn away from said back before folding whereby said sides may be folded flat upon said bottom, top, lid and front.

40 5. In a collapsible box, a back; a top hinged to said back; a lid hinged to said top; a bottom hinged to said back; a pair of sides; brackets extending forwardly from said back and provided with slideways; pins 45 at the outer ends of said slideways, and slotted plates attached to said sides and engaged by said pins, for the purpose described.

6. In a collapsible box, a back; a bottom hinged to said back and adapted to be folded 50 up against the same; a top hinged to said back and adapted to be folded down against the same; a closure hinged to said top and adapted to be folded down on said bottom; sides hinged to said back and adapted to be folded down on said top; bottom and closure, said sides being provided with edge flanges, and hook bolts mounted on said closure and adapted to engage said flanges when said box is set up.

60 7. In a collapsible box, a back; a bottom hinged to said back and adapted to be folded up against the same; a top hinged to said

back and adapted to be folded down against the same; a closure hinged to said top and adapted to be folded down on said bottom; means for securing the closure to said bottom when the box is set up; sides hinged to said back and adapted to be folded down on said top, bottom and closure, said sides being each provided with an edge flange, and 65 hook bolts mounted on said closure and adapted to engage said edge flanges when the box is set up.

8. A collapsible box consisting of a back; sides hinged to said back and having inwardly extending top and bottom flanges; a bottom hinged to said back and resting when extended upon said bottom flanges; a top hinged to said back and bearing upwardly when extended against said top flanges; a 70 closure hinged to said top, and means for securing said box in its set up condition.

9. In a collapsible box, a back; sides hinged to said back; a top hinged to said back; a closure hinged to said top; a bottom; vertical supports mounted on said bottom; load supporting rails mounted on said supports, and pivotal connection between 85 said rails and said back.

10. In a collapsible box, a back; a top hinged to said back; sides hinged to said back; a bottom; rails rigidly mounted on said bottom and having slots in their rear ends; brackets extending inwardly from said back; pivot pins extending through 95 said brackets and said slots and a closure hinged to said top.

11. In a collapsible box, a back; sides hinged to said back; said sides being provided with inturned bottom flanges; a top 100 hinged to said back; a bottom adapted to rest on said bottom flanges when said box is set up; vertical supports mounted on said bottom; rails rigidly mounted on said supports and pivotally attached to said back, 105 and a closure hinged to said top.

12. In a collapsible box, a back, sides hinged to said back, said sides and back being provided with inturned bottom flanges; a top hinged to said back; a closure hinged 110 to said top; a bottom adapted to rest upon said bottom flanges when the box is set up, and rails rigidly mounted on said bottom and pivotally connected with said back by means of pin and slot connection; said pivotal connection being such that the weight 115 of said bottom is carried by said flanges when the box is set up.

Signed at Pittsburgh, Pennsylvania, this 16th day of March, 1914.

WAYNE RAWLEY.
